14 Claims. (Cl. 99—182)

ABSTRACT OF THE DISCLOSURE

A process of packaging aseptically a fluid food product in a flexible container wherein a supply of the containers are stacked in a chamber and sterilized with oxide ethylene gas, the chamber is purged and filled with sterile air and the containers are filled alternately at filling stations with a sterile fluid food product and then passed through a water trap containing bactericidal material. The filled container then has a portion of the contents heat sealed from the rest of the package and this portion can be removed for testing without contaminating the remainder of the package.

This invention relates to a process of and apparatus for aseptically filling a sterile disposable package with a sterile food product. This invention further relates to a flexible walled package containing a sterile food product, and to a process of aseptically filling the same, and removing a sample portion without opening the sealed package.

Heretofore it has been impractical to fill a disposable flexible walled package with a sterile fluid under aseptic conditions. While it is common to aseptically can liquids in sheet metal containers, the present invention provides a method of filling a sterile fluid food product into a pre-sterilized flexible walled container in an aseptic environment.

The present invention specifically relates to the packaging of a sterile ice cream mix into a flexible plastic bag which is filled under aseptic conditions. Many states have stringent laws restricting the sale of ice cream mix and similar products, and particularly restricting the time which the products may be stored because of numerous spoilage problems in the usual non-sterile product. The subject sterile product may be stored for many months and the food product is still maintained in sterile condition.

In commercial practice, it is essential to test sterile food products to determine if the product is, in fact, sterile. A statistically significant number of samples must be tested to give the results reliability. In a typical lot of 500, 30 to 60 should be examined to comprise a significant number. Destructive sampling of such a large fraction of the product is very expensive, particularly when the individual packages are of large volume. Present testing methods inherently require that the sterility of the package be broken to make a test and thus expensive product is ruined. Accordingly another principal object of the present invention is to provide a package containing a sterile food product and a means for providing an attached removable representative sample which, when detached, does not impair the sterility of the remainder of the product in the package or of the sample.

These and other objects and advantages of the present invention will become apparent hereinafter.

In the accompanying drawings herein like numbers refer to like parts wherever they occur:

FIG. 1 is a diagrammatic respective flow diagram of the present invention;

2

FIG. 1a is similar to FIG. 1 but showing the chamber in greater detail;

FIG. 2 is similar to FIG. 1 but showing a side view;

FIG. 3 is a perspective view of the sample food package;

FIG. 4 shows the sample portion detached;

FIG. 5 is a side view of the detached sample;

FIG. 6 is a plan view of a germ culture package used to test the sterility of the empty packages; and

FIG. 7 is an enlarged view of a pour spout with foil cover attached.

FIG. 1 is a flow diagram of the present process and the various steps are set out in the blocks. Various details of the process steps will be explained in greater detail hereinafter.

FIG. 1a shows the bags being stacked in the chamber which subsequently is sealed, sterilized, vented, filled with sterile air, product contact surfaces sterilized, and readied for operation. (FIG. 1) The separately sterilized mix is passed to a timed switch valve 10 which delivers the product alternately to two filling nozzles 11 positioned in a sterile enclosed chamber 12. The sterile mix is passed to the valve 10 from a positive displacement pump (not shown) at a flow of approximately 6 gallons per 26 seconds. The product is at a temperature of approximately 80° F., the lower temperature being limited by the dew point within the chamber in order to avoid condensation on the surfaces of the pipes, and the upper temperature being limited by the flash point of the product being filled. The valve 10 is timed to alternate approximately every 26 seconds, since 6 gallon packages are conventionally filled in the chamber 12. The timing and delivery rate, of course, vary with the size package being filled and the designed flow rate of the process. However, since the product is metered by a positive displacement pump it is important that the flow through the valve 10 not be interrupted.

The sterile mixture may be prepared by any conventional method according to the particular product and the type of sterilization conditions preferred by the operator. Using an ice cream mixture, conventional processing techniques are employed including mixing, standardization, preheating, HTST sterilization, and homogenization which involves heating to about 300° F. for about 3.8 seconds. Other sterilization techniques are satisfactory, and different conditions may be used for other food products.

The chamber 12 is provided with operator arm holes 13 to which are attached arm length rubber gloves 14 by means of which the operator can reach into the chamber 12 and manipulate a sterile bag 15. The bags 15 are stacked in the chamber 12 and the operator manually attaches the bags 15 to the fill nozzles 11. After a bag 15 is filled, the operator detaches the bag 15 from the first filling nozzle 11 and moves it to a heat sealing assembly 16, where a seal is applied to the pour spout opening on the bag 15. This assembly is shown in copending Bowen application, Ser. No. 418,723 which is hereby incorporated into the present specification.

The operator then attaches another bag 15 to the first filling nozzle 11, so that when the bag 15 attached to the second filling nozzle 11 has been filled, the valve 10 will automatically switch the flow of fluid from the second fill nozzle 11 back to the first fill nozzle 11. The sealed filled flexible container 15 is passed through a sterile trap 17 onto a platform 18 and thereafter placed in a suitable paper board shipping container.

The chamber 12 is maintained with a sterile environment by the passage of sterile air under about one-half to three inches of pressure (water) and a temperature of about 60 to 80° F. The air is sterilized by heating it to

approximately 600° F. The air is cooled before it is passed to the chamber 12.

The liquid in the trap 17 is tap water having about fifty to four-hundred parts per million of chlorine. This provides a bactericidal liquid seal and insures sterility. Another advantage of the sterile trap 17 is that sterile tools in sealed packages can be passed from outside the chamber 12 through the trap or lock 17 to the workman manning the gloves 14 to repair the inside of the chamber 12 without affecting its sterility. This is important, since it is difficult to sterilize the chamber 12 and this avoids much interruption of the process flow that might otherwise occur. The chamber 12 is provided in its lower most part with an exhaust valve 20, which operates as a check valve and permits any water or product which may accumulate in the chamber 12 to be exhausted.

The chamber 12 and bags 15 are pre-sterilized prior to operation. A sufficient supply of bags 15 is stacked in the chamber 12 through a door 22 and germ culture packages 23 are interspersed in the stacks of bags 15. The chamber 12 is free of moisture and doors are placed over the water trap 17 and glove parts 13 prior to sterilization. Ethylene oxide gas or other suitable sterilizing gas is applied to the chamber 12 for 3 to 15 hours (preferably 6 to 8) to sterilize the chamber 12 and its contents, including the bags 15. A minimum of 385 milligrams of pure ethylene oxide per liter of contents (unit volume of container) is added to the chamber 12. There is no free water in the ethylene oxide. Moisture in the form of dry steam is introduced into the chamber to maintain 20 to 60% relative humidity and uniform chamber temperature is maintained at 60 to 120° F. and preferably at 80° to 110° F. With polyethylene bags, 125° F. is about the maximum temperature, although with polypropylene the gas can reach 250° F. The higher the temperature, the faster and more effective is the sterilization action of the ethylene oxide.

The germ culture package 23 comprises filter paper having one million bacterial spores per disc, and two discs per package 23 (the disc is about 1/2 inch in diameter). The discs are sealed in a plastic bag which is of the same material as the bags 15 to be filled. Approximately five test packets 23 are used per thousand bags 15. The bags are presumed to be sterile when all bacterial spores in the test packets are killed.

Before the filling operation starts the chamber 12 is exhausted of ethylene oxide by pulling a 26-inch vacuum on the chamber 12. The arm hatches 13 and the water trap 17 are covered. After the ethylene oxide is exhausted, the chamber 12 is filled with sterile air. This cycle is repeated again to assure all the ethylene oxide has been removed from the chamber 12. During filling, the sterile environment is maintained by the flow of sterile air through the chamber 12 as hereinbefore discussed.

The heat sealers 16, the tape rolls 29, and the fill nozzles 11 are operated by air cylinders which use sterile air which is exhausted into the chamber 12 to further insure sterility.

The preferred container 15 is of 4 mil polyethylene and is single walled. It has been found that double walled bags tend to inflate during the previously described evacuation and refilling process.

The seal 29 is of foil backed polyethylene.

Packages are randomly selected from each day's production for statistical evaluation of sterility. The packages are incubated for 72 hours at 80° F., after which they are agitated by shaking and sampled as hereinafter described.

The sample 19 is formed by applying a double heat seal to one corner of the bag. Thus, the sample portion 19 has a sealed edge 24 and the bag 15 also has a sealed edge 25. To remove the sample 19, a cut is made (shown by the broken lines 26 in FIG. 3) between the sealed edges 24 and 25. Thus, a small, sealed sample representative of the entire contents of the primary package can be removed without impairing the integrity and value of the

primary package. Thereafter a corner of the sample 19 is severed with a sterile hot wire and the sample product can be removed without contamination for inoculation into nutrient broth with further incubation to determine sterility and for direct microscopic examination.

Another advantage of the present package is that a reclosable feature is provided, so that the purchaser, after opening the sealed package, can reclose it if all the product is not used immediately. The rigid pour spout 27 is provided with threads 28 so that the purchaser, after removing the heat-sealed over-wrap 29 can apply a screw cap to reseal the container 15. Other types of closures can be used, such as snap-caps, friction caps, etc.

Other forms of openings in the containers 15 can be used instead of the rigid pour spouts 27, although these are presently preferred.

In addition to ice cream mix, other fluid or semi-fluid food products which can be aseptically packed, such as milk evaporated milk, cream, fruit juice, tomato puree, etc., are suitable for use in the present process.

Thus, it is seen that the present invention provides aseptic filling process and production which achieves all the objects and advantages sought therefore.

This invention is intended to cover all changes and modifications of the examples of the invention herein considered for the purpose of the disclosure and does not constitute departure from the spirit and scope of the invention.

What is claimed is:

1. A process of packaging aseptically a fluid food product including the steps of:

- (a) sterilizing flexible walled containers each having rigid pour spouts,
- (b) maintaining a sterile filling environment,
- (c) supplying a sterile, fluid food product continuously to the sterile environment,
- (d) filling the sterile containers through the pour spout, with the sterile food product, while maintaining the sterile environment,
- (e) applying a fluid tight seal to open end of the pour spout of the filled container,
- (f) exiting the filled sealed container from the sterile environment through a trap filled with a bactericidal liquid without contaminating the sterile environment, and
- (g) sealing off a segment of the filled container, thus trapping a portion of the container's contents without opening the container.

2. A process of packaging aseptically a fluid ice cream product including the steps of:

- (a) sterilizing flexible walled polyethylene containers of about 4 mil thickness having rigid pour spouts attached thereto,
- (b) maintaining a sterile filling environment,
- (c) metering a sterile ice cream mix continuously to the sterile environment,
- (d) filling the sterile containers with the ice cream mix while maintaining the sterile environment,
- (e) applying a fluid tight seal to the open end of the pour spout of the filled container,
- (f) exiting the filled sealed container from the sterile environment without contaminating the same,
- (g) sealing off a segment of the filled container, thus trapping a portion of the container's contents without opening the container, and
- (h) removing the sealed off portion without contaminating the rest of the container's contents.

3. A process of packaging aseptically a fluid product including the steps of:

- (a) placing flexible walled plastic containers having openings therein into an enclosed chamber,
- (b) filling the chamber with ethylene oxide to sterilize the container,
- (c) purging the ethylene oxide with sterile air,

- (d) maintaining a sterile air filling environment in the chamber,
  - (e) supplying a continuous supply of sterile, fluid food product under positive displacement flow alternately to fill stations in the chamber,
  - (f) filling the sterile containers alternately at the fill stations with the sterile food product, while maintaining the sterile air environment,
  - (g) moving the filled containers to a heat sealing apparatus in the chamber,
  - (h) applying a fluid tight heat sealed cover to the filled container openings, and
  - (i) exiting the filled sealed container from the chamber through a liquid seal filled with sterilizing fluid without contaminating the sterile environment of the chamber.
4. The process of claim 3 including the steps of sealing off a corner of the filled container, sealing off a segment of the filled container, thus trapping a portion of the container's contents without opening the container, and removing the sealed off portion without contaminating the rest of the container's contents.

5. A process of packaging aseptically a fluid food product including the steps of:

- (a) providing a supply of individual preformed un-sterile collapsible commercial containers,
- (b) sterilizing said containers at a sterilizing station,
- (c) maintaining a sterile filling environment,
- (d) supplying a sterile, fluid food product to a filling station in the sterile environment,
- (e) joining the sterile containers to the sterile food product supply at the filling station,
- (f) filling the sterile containers with the sterile food product, while maintaining the sterile environment,
- (g) sealing the opening in the filled container through which the container has been filled to maintain sterility of the contents,
- (h) exiting the filled sealed container from said environment through a liquid seal filled with sterilizing

fluid without contaminating the sterile environment of the chamber.

6. The process of claim 5 wherein the containers are stacked in collapsed condition during sterilization.

7. The process of claim 6 wherein the containers are single wall polyethylene of about 4 mil thickness.

8. The process of claim 5 including the step of stacking the containers in collapsed condition in the sterile filling environment during sterilization and individually transferring the sterile containers to the filling station.

9. The process of claim 5 wherein the filled container is passed through a water trap containing bactericidal material in exiting from the sterile environment.

10. The process of claim 5 including the steps of positioning the containers in stack during sterilization, placing germ culture pack in the stack and removing the pack to test the efficacy of the sterilization of the containers prior to filling the same.

11. The process of claim 5 including the steps of supplying the sterile fluid food product to a plurality of filling stations in the sterile environment, and alternately filling sterilized containers at said filling stations.

12. The process of claim 5 including the step of sealing off a segment of the filled container, thus trapping a portion of the container's contents.

13. The process of claim 5 wherein the fluid food product is ice cream mix.

14. The process of claim 5 including the step of supplying a positive flow of sterile air to the filling environment.
